ABSTRACT OF THE DISCLOSURE

A machine for removing pile from the edge of mats having a sheet base onto which a fiber pile is attached, consists of a housing having a side opening and a bottom plate. In the housing, a downwardly-projecting driven shaft is mounted, and a rotary cutting blade is attached to the shaft above the plate, with its outermost edge projecting through the opening of the housing. The innermost edge of the blade is raised about 0.08" to 0.12" above the outermost edge. Pressure fingers mounted on the plate hold the mat edge against the plate during the cutting operation.

Background of the invention

In recent years, outdoor link mats have been gradually replaced by mats having a plastic or rubber base onto which a weather-resistant pile of nylon or similar synthetic fiber is attached. The usual base is a sheet of vinyl polymer having a thickness of about 0.1". Such mats are usually made in rolls of, say 3 ft. width, and the sides of such mats have an edge of bare vinyl plastic of about 1" width. When a mat of desired length is cut from such a roll, it is apparent that the two ends will not have the bare plastic edging like the sides, but will have the pile showing to the very edge of the mat. In order to give the mat a uniform appearance and proper trim, it has been the practice to attach to these edges a strip of bare plastic to match the sides.

These plastic edging strips have been applied either by cementing or heat sealing them to the plastic base at the edge of the mat. However, after some use, it has been found that such heat sealed or cemented edgings break away from the mat with a consequent tripping hazard, or unsightly mat being presented. Also, during cleaning of these mats, such edging has a tendency to break off where the mat is being grasped by the edging. Another disadvantage of such edgings is that they are not adapted for use on arcuate or circular edges or on mats having intricate shapes. A further objection is that the application of such edging is expensive. There has been need for some way of providing such edging which will not involve these inconveniences, dangers and disadvantages.

Summary of the invention

According to the present invention, a machine has been developed which employs a rotary cutting blade operating at high speed. This blade is mounted in a downwardly-directed shaft housing having a bottom plate over which the mat edge is pulled. The blade projects beyond the housing and is adjusted to just clear the plastic base of the mat so that, as the mat edge is pulled on the bottom plate, the pile at the mat edge is cut off by the blade for the required distance. By tilting the blade upwardly for a distance of about 0.08" to 0.12", at the innermost edge, burning of the mat by friction is avoided.

By this means, it has been found possible to effect a proper edging on the mat ends, which edging has the

2

same strength as the edging on the sides. Also, the operation is less expensive, and no deterioration or damage results during the cleaning of the mat. Furthermore, the cutting operation is just as easily performed on mats having intricate shapes, so that there is no necessity for special plastic edgings as has been the case heretofore.

Brief description of the drawings

The invention will be more readily understood by reference to the accompanying drawing in which a preferred embodiment is described, and in which:

FIG. 1 illustrates a top or plan view of a preferred embodiment of the invention.

FIG. 2 depicts a side elevational view thereof.

FIG. 3 presents an enlarged top cross-sectional view taken along the plane of line 3—3 in FIG. 2.

FIG. 4 shows an enlarged cross-sectional front view taken along the plane of 4—4 in FIG. 3.

The same numerals refer to similar parts in the various figures.

Description of the preferred embodiments

Referring to the drawing, numeral 10 indicates generally a machine for providing an edging on mats, according to the present invention. It involves a housing 11 having a motor section 12, a switch section 13, and a rotor section 14, from the side of the latter of which projects a handle 15. A cord 16 is used to plug into a source of electric current. The motor, switch and rotary drive are of conventional design, and a trigger switch 17 has been found most convenient for the operation.

The rotor housing 14 has a driven shaft 18 mounted in a downwardly-directed housing 19. To the bottom of this shaft is attached, by means of nut 20, a rotary cutting blade 21, which projects through a cut-off portion 19' of the shaft housing 19. Blade 21 is raised above the bottom plate 22 of housing 19 for the required distance to just clear the plastic base 23 of mat 24, from which projects upwardly the pile 25 to be cut. Since the blade 21 rotates at a speed of about 1950 r.p.m., it has been found desirable to raise the innermost edge 21' of blade 21 about 0.01" higher than the outermost edge 21" of the blade. This eliminates burning or heating up of the mat or base because of friction. A stationary flat cover plate 26 is also disposed over most of the projecting blade portion 21" as a safety precaution. Downwardly-depressing spring fingers 27, 28 and 29 have their rearward ends mounted on support 30 attached to shaft housing bottom plate 22 (by screws 31), and these fingers press mat 24 down against plate 22 as the mat is pushed forwardly for the shearing operation. The mat is pushed or pulled forwardly in the direction of the arrow in FIG. 3, and, as the edge 32 of the mat passes under blade edge 21" (FIG. 4), the blade cuts off the pile from the plastic edge 32 for the desired distance.

It has been found that, for most mats, a blade of 4" diameter is satisfactory. Such a blade is desirably of hollow ground steel having a thickness of about 0.049". The blade edge 21" projects beyond guard plate 26 for a distance of about $\frac{1}{8}$ ". The aforementioned tilt of blade 21 is for a distance of about 0.08" to 0.12", with respect to opposite edges of the blade.

We claim:

1. A machine, as described, for shearing the edge of a mat having a sheet base onto which a fiber pile is attached, comprising:

a housing having a side opening and a bottom plate, a downwardly-directed driven shaft mounted in said housing,

a rotary cutting blade mounted on said shaft above said plate and having an edge projecting through said opening and having its innermost edge disposed somewhat higher than its outermost edge, in a manner such that, as a mat edge is fed on said plate under said outermost blade edge, said blade edge may clear said mat base and cut off the pile therefrom for the required distance.

2. A machine, according to claim 1, in which said plate is provided with a raised mounting on which are mounted spring fingers designed to press said mat onto said plate as said mat edge is fed under said blade.

3. A machine, according to claim 1, in which the innermost edge of said blade is raised for a distance of about 0.08" to about 0.12" above the outermost edge.
